(57) **CLAIM**

The ornamental design for a plasma torch electrode, as shown and described.

DESCRIPTION

FIG. 1 is a perspective view of a plasma torch electrode showing our new design;

FIG. 2 is a bottom view thereof;

FIG. 3 is a top view thereof;

FIG. 4 is a left side view thereof;

FIG. 5 is a right side view thereof;

FIG. 6 is a front view thereof; and,

FIG. 7 is a back view thereof.

The dotted and/or broken lines depict environmental features, or the character or contour of the surfaces represented and are not a part of the claimed design.

1 Claim, 6 Drawing Sheets**FIG. 1**

FIG. 2

FIG. 3

FIG. 4

FIG. 5

FIG. 6

FIG. 7
